CLAIM

I claim the ornamental design for a rope fastening and tensioning device, as shown and described.

DESCRIPTION

FIG. 1 is a perspective view of the rope fastening and tensioning device viewed from the bottom and the left;

FIG. 2 is a front view of the rope fastening and tensioning device of FIG. 1;

FIG. 3 is a rear view of the rope fastening and tensioning device of FIG. 1;

FIG. 4 is a right side view of the rope fastening and tensioning device of FIG. 1;

FIG. 5 is a left side view of the rope fastening and tensioning device of FIG. 1;

FIG. 6 is a top plan view of the rope fastening and tensioning device of FIG. 1;

FIG. 7 is a bottom plan view of the rope fastening and tensioning device of FIG. 1; and,

FIG. 8 is another perspective view of the rope fastening and tensioning device of FIG. 1 viewed from the top and the right.
